UNITED STATES PATENT OFFICE.

CLARENCE E. LOMAX, OF OAK PARK, ILLINOIS, ASSIGNEE, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed April 12, 1926. Serial No. 101,234.

This invention relates in general to automatic telephone systems in which connections are established through the medium of subscriber controlled automatic switches, but is 5 more particularly concerned with such automatic telephone systems as include party lines and selective ringing equipment at the central exchange.

In any telephone system, in order to establish a talking connection with a particular party on a party line, some means must be provided for signaling the particular party on the line with which a calling subscriber wishes to communicate, and this preferably

15 without actuating the bells at the other substations on the same line. Numerous methods of selectively signaling a particular party on a party line have been proposed and are in use. The method in common use by the Bell 20 Telephone Company throughout the United States is one which depends for this selective action on the use of positive or negative ringing current impulses applied to either one or the other side of the line.

25 In the patent to Martin No. 1,524,194, an adaptation of this method to automatic telephone systems is described. In this system, each party line is made accessible to the connectors of four different groups, the connectors of each group being arranged to supply ringing current impulses of a certain kind over a certain side of the line to signal a certain one of four parties on the line. This system, while satisfactory from an operating point of view, requires the use of more connector switches per one hundred lines than would be necessary if all the connectors having access to the one hundred lines were in one large group.

30 The principal object of the present invention is the provision of a new and improved connector switch having an individual means for selecting the kind of ringing current impulses and the side of the line to which they are to be applied, for particular use in a full 35 selective four-party line telephone system in which full selection is obtained by the application of either positive or negative current impulses to one or the other side of the line.

40 By the utilization of this new and improved connector switch in the above described system, the number of connectors needed for a certain number of party lines will be considerably less than are necessary when the party

lines are accessible to the connectors of four 55 different groups.

The invention, its object and other features not specifically mentioned, will be described in detail hereinafter, reference being had to the accompanying drawing, in which is shown 60 sufficient of the apparatus in an automatic telephone system to enable the invention to be explained and understood.

The reference character A indicates an automatic substation of the usual type, which 65 has the usual talking instrumentalities and the calling device S for controlling the central office switches.

Substation A is connected with the central exchange by line conductors 11 and 12 which 70 terminate in the individual line or trunk selecting switch C. The line switch C is a switch of the well known rotary type whose wipers have no normal position and move in a forward direction only. As is well known, the 75 function of the individual line switch is to extend its associated line to an idle selector switch when the receiver is raised at the substation to initiate a call.

One of the first selector switches, to which 80 the line switch C has access in common with other similar line switches, is indicated in the drawing by the rectangle D. Inasmuch as selector switches are well known in the art, it has not been considered necessary to 85 show the circuits in detail. It may be stated briefly that the selector D is a Strowger vertical and rotary switch of well known mechanical construction, and operable according to the two-wire system of control. When used in setting up a connection in the system as shown in the drawing, the selector responds to the first digit in the called number in order 90 to select a desired group of connectors, after which the selector automatically rotates to select and connect with a trunk line extending to an idle connector in the selected group. The above is, of course, true only of a one thousand line system; if the capacity of the 95 system is greater than this, second or third 100 selectors will be interposed between the first selectors and connectors in the well understood manner. This is in accord with the usual percentage trunking system, however, and need not be discussed in detail.

One of the trunk lines to which the selector D has access is shown in the drawing as extending to the connector E, which is also a

Stronger vertical and rotary switch having a capacity of one hundred subscribers' lines. The connector E is operable according to the two-wire system of control, similar to the selector D, and responds to the next two digits in a called number to complete the connection to the called line.

One of the party lines to which connector E has access comprises line conductors 111 and 112 to which the substations A¹ to A⁴, inclusive, are connected. These substations are of the well known type used in the above described type of full selective party line system, the substation A⁴ being shown in full and only the ringing circuits of substations A¹, A², and A³ being shown. The line switch C' is associated with this party line at the central exchange, and is similar to line switch C.

Just below the connector E, the auxiliary switch F is shown, which is individual to the connector E. This switch, comprising the wipers 122 and 123 and their associated sets of banks, the stepping magnet 120, and the release magnet 121, constitutes with its control-line circuits the means above referred to which predetermines the kind of ringing current impulses and the side of the line to which they are to be applied for signalling a particular subscriber on a party line. Switch F performs this function responsive to the dialing of the last digit in the called number.

The common ringing equipment for producing positive pulsating current and negative pulsating current comprises the A. C. generator G, the three additional batteries B¹, B², and B³, and the interrupter I, the battery B being the regular exchange battery. With the connections as shown, positive pulsations are intermittently impressed on conductor 142 and negative pulsations are intermittently impressed on conductor 141. The battery B³ and the exchange battery B serve as "tripping" batteries for operating the ring cut-off relay in the connector when a subscriber answers a call during the silent period.

With this general description of the system and the apparatus used in mind, a further understanding of the invention may be gained from a detailed description of the operations which take place when one subscriber calls another subscriber on a party line. For this purpose it will be assumed that the subscriber at substation A desires to establish a connection with a subscriber at substation A⁴. When the receiver is removed at the calling station, a circuit is completed over the conductors 11 and 12 for the slow acting line relay 15. Upon energizing, relay 15 closes a circuit at its armature 20, which includes the

winding of the switching relay 14 and the stepping magnet 16 in series; and at its armature 21 connects the test wiper 26 to the above circuit at a point midway between the said switching relay and the magnet. The operation now depends upon whether the trunk

line with which the line switch wipers are associated is busy or is not busy. If the trunk line is busy, there will be a ground potential upon the test contact with which the test wiper 26 is in engagement, the switching relay 14 will be short circuited, and the stepping magnet 16, which interruptes its own circuit, and will be operated in the manner of a buzzer to advance the switch wipers in search of an idle trunk line. We may assume, in the present case, that when the call is initiated the wipers are advanced to the idle trunk terminating in bank contacts 28-30, inclusive. When the wipers arrive at this set of contacts the short circuit is removed from the switching relay 14 and the operation of the stepping magnet 16 will cease because of the high resistance of the said switching relay. The latter relay, however, is energized and grounds the test wiper 26 at its armature 18, and at its armatures 17 and 19 disconnects the line conductors 11 and 12 from the winding of the line relay 15 and from ground, respectively, and extends them by way of wipers 25 and 27, and bank contacts 28 and 30 to the line relay (not shown) of the first selector D. The line and release relays of the selector D are now energized in the usual manner and the latter relay grounds the release trunk conductor of the trunk line in order to establish a holding circuit for the switching relay 14 of the line switch C. This operation is well understood and need not be explained further.

The calling subscriber may now operate his calling device in accordance with the first digit in the desired number. In response to the interruptions in the line thus produced, the vertical magnet of the selector D is operated under control of the line relay to raise the wipers 40-42, inclusive, to the particular level in which are terminated the trunk lines extending to the desired group of connector switches. Thereafter the rotary or trunk selecting movement is initiated automatically in the usual manner, and the wipers are rotated in search of an idle trunk line. Assuming that the trunk line shown in the drawing is the first idle trunk line, then when the wipers arrive at bank contacts 43-45, inclusive, the test wiper 41 will find no ground potential upon the test contact 44, and the rotation of the switch will cease. When this occurs, the incoming line conductors are extended in the usual manner by way of the switch wipers 40 and 42, bank contacts 43 and 45, and contact springs controlled by the reversing relay 50 to the windings of the double wound relay 51 of the connector E.

When the line is extended as above described, the line relay 51 is energized over the line circuit to close a circuit for the slow-acting release relay 52. Upon energizing, relay 52 prepares a circuit for the vertical magnet 58 at its armature 67, and at its armature

65 connects ground to the release trunk conductor 47, thereby completing a holding circuit for the selector D and the line switch C in the well known manner. The calling subscriber may now operate his calling device in accordance with the next digit in the desired number. As a result, the line relay 51 is deenergized a plurality of times, and at the first deenergization transmits a current impulse to the vertical magnet 58 over the following circuit: grounded armature 64 and its resting contact, armature 67 and its working contact, off normal springs 61 and 63, winding of the slow to release series relay 53, and the winding of the vertical magnet 58 to battery. By the operation of the vertical magnet, the wipers 90-92, inclusive, are raised step by step until they stand opposite the level in which is terminated the line to substation A⁴. The slow to release series relay 53 is energized in series with the vertical magnet and by means of its armature 68 maintains the circuit of the vertical magnet intact after the off normal springs have been shifted, which occurs on the first vertical step. At the end of the vertical movement of the switch, relay 53 is deenergized and transfers the operating circuit to the rotary magnet 59.

The subscriber will now operate his calling device in accordance with the next digit of the desired number, which is the last digit which has to do with the line selection. When the calling device is operated, the line relay 51 responds as before and sends impulses to the rotary magnet 59 over the following circuit: grounded armature 64 and its resting contact, armature 67 and its working contact, off normal springs 61 and 62, armature 68 and its resting contact, resting contact and armature 75, armature 85 and its resting contact, and the winding of the rotary magnet 59 to battery. By the operation of the rotary magnet, the wipers 90-92, inclusive, are rotated step by step and are finally brought to rest in engagement with the bank contacts in which the line to substation A⁴ terminates, these bank contacts being indicated in the drawing by the reference characters 93, 94 and 95. The slow to release relay 56 is energized in multiple with the rotary magnet and retains its armature attracted throughout the rotary movement of the switch. At its armature 78, relay 56 connects the test wiper 91 with the test relay 55, and at its armature 79 the said relay 56 closes a shunt around the contact at armature 75 of the test relay. The latter operation is to prevent the test relay from opening the rotary magnet circuit while the test wiper is passing over busy test contacts.

It will be assumed first that the called line is busy. Such being the case, when the test wiper 91 arrives at test contact 94, it will find a ground potential thereon, the test relay

55 will be energized, and when the slow to release relay 56 deenergizes at the end of the rotary movement of the switch, the test relay 55 establishes a locking circuit for itself at its armature 74. Relay 55 also opens the rotary magnet circuit at its armature 75, thus rendering the impulse circuit ineffective at this time in case the calling subscriber dials the last or ringing current selecting digit. Relay 55 also at its armature 77, connects a lead from the busy signaling machine BM to the lower heavy talking conductor. By this latter operation, an audible signal is transmitted to the calling subscriber, and, being advised thereby that the called line is inaccessible for the time being, he will hang up his receiver.

Having explained the operations which take place when the called line is busy, it will now be assumed that the line is idle when called. Under these circumstances, when the test wiper 91 arrives at test contact 94, it will find no ground potential and the test relay 55 will not be energized. Then when the slow to release relay 56 deenergizes at the end of the rotary movement of the switch, a circuit is completed for the slow acting switching relay 57 as follows: From the grounded release trunk conductor 47 by way of armature 74 and its resting contact, upper winding of the switching relay 57, resting contact and armature 78, test wiper 91, test contact 94, winding of the switching relay 114, and the winding of the stepping magnet 116 to battery. Relays 57 and 114 are energized in series over the above circuit, and the latter relay is operated to clear the called line of its normal battery and ground connections in the line switch C. It should be noted that the relay 114 is not fully operated at this time, due to a mechanical interlocking arrangement between the armature of this relay and the armature of the slow acting line relay 115, and the wipers of the line switch C¹ are not connected up. In the connector E, switching relay 57, in energizing, establishes a locking circuit for itself at its armature 84, grounds the test wiper 91 at armature 83, transfers the impulsive circuit from magnet 59 to the stepping magnet 120 of the ringing current selecting switch F at its armature 85, and prepares a circuit at its armature 86 which provides for transmitting a tone signal to the calling subscriber during the ringing operation.

The calling subscriber may now operate his calling device in accordance with the final digit in the number, which is the digit which determines the proper ringing current and the side of line to which it is to be applied for signalling the particular station wanted. The substations A¹-A⁴, inclusive, have been numbered for convenience in accordance with the digits to which they correspond, and since the substation A⁴ is the wanted substation in

the present case, the final digit to be called will be the digit 4. When the calling device is operated for this digit, the line relay 51 transmits four impulses of current to the stepping magnet 120 of the switch over the following circuit: From grounded armature 64 and its resting contact, armature 67 and its working contact, off normal springs 61 and 62, armature 68 and its resting contact, resting contact and armature 75, armature 85 and its working contact, and the windings of the stepping magnet 120 to battery. By the operation of magnet 120, wipers 122 and 123 are given a step by step movement and are finally brought to rest in engagement with the fourth contacts in their respective banks. The slow to release relay 56 is energized in multiple with the magnet 120 and now serves to prevent the energization of relay 55 by holding open its energizing circuit at armature 80, which circuit will be explained hereinafter.

With wipers 122 and 123 in engagement with the fourth contacts of their respective banks, a circuit for the signal control relays 131 and 132 is closed which may be traced from ground by way of armature 66 and the working contact, wiper 122 in engagement with a fourth bank contact, through the winding of relay 131 to battery; and from ground by way of armature 66 and the working contact, wiper 123 in engagement with its fourth bank contact, through the winding of relay 132 to battery. Both relays 131 and 132 are energized and perform the following circuit changes: At armature 133 and the working contact, the common ringing conductor 142 is connected to the upper terminal of the upper winding of the ring cut-off relay 54. The lower terminal of the upper winding of ring cut-off relay 54 is connected by way of armature 134 and the working contact and armature 136 and the working contact to the ringing conductor 144. At armature 135 and the working contact, ground potential is connected to the conductor 143. These operations prepare the signalling circuit, predetermining the kind of signalling current and the side of the line to which it is to be applied.

At the end of the series of impulses transmitted to magnet 120, relay 56 is deenergized and completes the circuit for relay 55 as follows: ground by way of springs 124 which close on the first rotary step of the selector switch F, resting contact and armature 80, through the winding of relay 55, which now functions as a ringing circuit control relay, to battery. Relay 55 now energizes and performs the following circuit changes: At armature 77 a circuit is closed for the ring back tone which may be traced from conductor 96 connected to the ring back tone source, working contact and armature 86, working contact and armature 77, normally closed springs controlled by armature 71, to the lower heavy talking conductor. By this means a ring

back tone is transmitted to the calling subscriber to apprise him that the called subscriber is being signalled. At armature 73 the circuit for the release magnet 121 of the switch F is prepared. At armature 75 the impulsing circuit is opened thereby making any further manipulation of the dial at the calling substation ineffective. At armatures 72 and 76 the signalling circuit is completed which may be traced as follows: from common ringing conductor 142, to which positive ringing current impulses and positive battery are alternately connected, working contact and armature 133, the upper winding of the ring cut-off relay 54, armature 134 and 75 the working contact, armature 136 and the working contact, conductor 144, working contact and armature 76, resting contact and armature 71, armature 87 and the working contact, wiper 92, bank contact 95, line conductor 80 112 through the winding of the A. C. relay 103 at substation A³ to ground, and through 90 the winding of the A. C. relay 104 at the substation A⁴ to ground. Due to the condensers in series with the A. C. relays at the substations, alternating currents are set up in the two A. C. relays 103 and 104. Responsive thereto, these relays operate and connect the ringers 154 and 153 directly across the line conductors. As soon as these ringers are connected across the line, pulsating current will 95 pass through the two ringers over the above traced circuit from conductor 112, and by way of the armatures of the A. C. relays and their working contacts, line conductor 111, bank contact 93, wiper 90, working contact and armature 81, armature 69 and resting contact, armature 72 and the working contact, ringing conductor 143, working contact and armature 135 to ground. The ringers at the substations 100 are biased in the ordinary way. Ringer 153 is adapted to respond only to negative pulsating current, while ringer 154 is adapted to respond only to positive pulsating current. It follows therefore that since the current is 105 being supplied from the positive pulsating ringing conductor 142 only the ringer 154 will respond.

In this manner the subscriber at substation A³ is selectively signalled until he answers the 110 call or until the calling subscriber replaces his receiver. It may be mentioned at this time that the ring cut-off relay 54 is so adjusted that it will not operate responsive to the ringing current impulses or to the current supplied from the tripping battery B³ during the silent period, the current in both instances being limited by the comparatively high resistances at the substations.

When the subscribers at substation A⁴ removes his receiver to answer the call, however, a low resistance bridge is placed across the line conductors including the transmitter and the primary winding of the induction coil 125 at the called substation. The flow of current 130

in the circuit including the two line conductors in series is thereby sufficiently increased to cause the instant operation of the ring cut-off relay 54, this current being either 5 from the battery B' in series with generator G (at any time when this battery is not directly opposed by the A. C. generator G) or by current from the tripping battery B³ connected to the common ringing conductor 142 10 during the silent period. Upon energizing, relay 54 closes the locking circuit for itself at armature 70, and at armatures 69 and 71 and their working contacts the talking connection from the substation A to the substation 15 A⁴ is finally completed, the signaling circuit being opened at the resting contacts of these armatures. The ring back tone circuit is also opened by the separation of the normally closed springs controlled by armature 71. As 20 soon as the talking connection is completed to the called line, the back bridge relay 50 operates over the called line loop and performs the usual operation of reversing the battery connections to the calling line. This 25 latter operation is of no utility in connection with the apparatus shown, but is the standard operation for use in controlling measured service equipment when such equipment is supplied and is therefore included.

30 Conversation may now proceed as desired, and when the subscribers are through they will both replace their receivers. Replacing the receiver at the called substation merely causes the deenergization of the back bridge 35 relay 50 which thereupon restores its armatures to normal. In response to the replacement of the receiver at the calling substation, the line relay 51 deenergizes after which the release relay 52 is deenergized. In deenergizing, relay 52 initiates the release of the 40 entire connection in the usual manner. By the restoration of armature 65 ground is removed from the release conductor 47, thereby permitting the selector D and line switch C to 45 restore to normal in the usual manner. In addition thereto, the circuit for the release relay 121 of the switch F is closed which may be traced from ground by way of armature 65 and resting contact, armature 73 and the 50 working contact, through the winding of the release magnet 121 to battery. Release magnet 121 operates and restores the wipers 122 and 123 of the switch F to normal. The release of armature 66 opens the circuit of relays 131 and 132, and switching relay 57, 55 which likewise restore to normal. By the release of armature 64 and armature 67, the usual circuit for the release magnet 60 is closed. In operating, release magnet 60 restores the switch wipers 90, 91 and 92 to 60 normal in the well known manner. When the wipers of the switch F return to normal, springs 124 are separated. This opens the circuit of relay 55 which thereupon deenergizes and restores its armatures to normal. 65

All the apparatus used in the establishment of the connection is thus freed and may be used in the establishment of another connection.

An explanation will now be given of the manner in which a connection with the other three stations on the party line may be established. The substations A¹, A², and A³ may be reached by dialing the same party line number and by dialing the digits 1, 2 and 3, 70 respectively, as final digits. The operations performed in establishing a connection with any one of the other three substations are exactly the same as when establishing a connection to the substation A⁴, with the exception of 75 the operations of relays 131 and 132 which controls the polarity of the pulsating signaling current and the line conductor to which it is applied, which in turn predetermines which of the four ringers is to operate. Should a 80 calling subscriber desire to converse with the subscriber at substation A³, he will dial the same line number and then dial the digit 3 as the final digit. In response to dialing the 85 line number, the selector D and the connector E, assuming that these switches are again taken for use, operate in the manner described above. In response to the dialing of the final digit 3, wipers 122 and 123 of the switch F are positioned on the third set of contacts in their 90 respective banks. In this case no circuit is closed for the relay 131, but a circuit is again closed for relay 132. The common ringing conductor 141 then remains connected to the lower terminal of the upper winding of relay 95 100 104. Ground is again connected to the ringing conductor 144 at armature 135 and the working contact, and the upper terminal of the upper winding of relay 54 is connected to 105 ringing conductor 144 by way of armature 133 and the resting contact and armature 136 and 110 the working contact. The signaling circuit is identical to that traced for signaling the subscriber at substation A⁴, except that negative pulsating current from the common ringing 115 current conductor 141 instead of positive pulsating current from conductor 142 is used. Both relays 104 and 103 at the substations A¹ and A² operate as before. Ringer 154 will 120 not respond to negative pulsations. Ringer 153 is adapted to respond to negative current impulses and therefore operates whenever it is bridged across the line by operation of relay 103, thereby signaling the subscriber at substation A³.

To signal the subscriber at substation A, the final digit to be dialed is the digit 2. In this case the wipers 122 and 123 of switch F are positioned on the second contacts in their respective banks. In this case, relay 131 operates and relay 13 remains deenergized. Ground is now connected to conductor 144 by way of armature 135 and the resting contact, and positive current impulses are supplied from conductor 142 by way of the working 125 130

- contact and armature 133 through the upper winding of relay 54, armature 134 and the working contact, armature 136 and the resting contact, conductor 143, from where the circuit 5 extends by way of working contact and armature 72, resting contact and armature 69, armature 81 and the working contact, wiper 90, bank contact 93, line conductor 111, through the A. C. relay 102 at substation A² and the 10 A. C. relay 101 at substation A¹ in parallel to ground. Relays 102 and 101 operate responsive to the signaling current impulses in the same manner as did relay 104 and 103. The ringer 152 is biased the same as ringer 154, 15 and ringer 151 is biased the same as ringer 153. Ringer 152 therefore operates responsive to the positive current impulses when connected across the line conductors to signal the subscriber at substation A².
- 20 To signal the subscriber at substation A¹, the final digit to be dialed is the digit 1. In response to the dialing of the digit 1, after the line number is dialed, the wipers 122 and 123 are positioned on the first contact in their 25 respective banks. Neither relay 131 nor relay 132 is operated in this case. The signaling circuit is the same as that for signaling the subscriber at substation A² except that negative current impulses are now supplied from the common conductor 141, to which the ringer 152 is not responsive, and to which the ringer 151 responds to signal the subscriber at 30 substation A¹.

It is evident from the drawing and the 35 above description that relay 131 performs the function of selecting the source of ringing current and that relay 132 performs the function of determining to which side of the line the selected source of ringing current is to be connected. Relay 131 also reverses the 40 connections to the upper winding of relay 54 when the ringing current from conductor 142 is selected. In so doing, the current flow through the upper winding of relay 54 is made to flow in one direction regardless of 45 whether positive current impulses or negative current impulses are used, this being the same as the direction of current flow in the lower winding of relay 54 when the circuit of the lower winding is closed at armature 50. Such a provision is obviously necessary for 55 the satisfactory operation of the cut-off relay 54.

This completes the description of the operation of the new and improved connector switch and its features. What is considered new and is desired to have protected by Letters Patent will be specifically stated in the appended claims.

60 What is claimed is:

1. In a party line system, a connector switch for extending calls from a calling line to a called party line, sources of positive and negative signalling current, a signalling circuit, a cut-off relay in said switch adapted for

inclusion in said circuit and operative responsive to the answering of a call by a called subscriber to interrupt said signalling circuit, and means in said switch directly controlled over a calling line for controlling 70 the selection of the source of signalling current and for controlling the connections of said cut-off relay in said signalling circuit so that the direction of current through the winding of said cut-off relay is the same regardless of 75 the source selected.

2. In a party line system, a connector switch for extending calls from a calling line to a called party line, sources of positive and negative signalling current, a signalling circuit, a cut-off relay in said switch adapted for inclusion in said circuit and operative responsive to the answering of a call by a called subscriber to interrupt said signalling circuit, means in said switch for controlling the selection of the source of signalling current and for controlling the connections of said cut-off relay in said signalling circuit so that the direction of current through the winding of 80 said cut-off relay is the same regardless of 85 the source selected, and means in said switch for determining the side of the line to which the selected source is connected.

3. In a party line system, a connector switch for extending calls from a calling line to a called party line, sources of positive and negative signalling current, a signalling circuit, a cut-off relay in said switch adapted for inclusion in said circuit and operative responsive to the answering of a call by a called subscriber to interrupt said signalling circuit, means in said switch for controlling the selection of the source of signalling current and for controlling the connections of said cut-off relay in said signalling circuit so that the direction of current through the winding of 90 said cut-off relay is the same regardless of 95 the source selected, and means in said switch for determining the side of the line to which the selected source is connected.

4. In a telephone system, a party line, sources of positive and negative signalling current, a connector switch, means for operating said connector to connect with said line, means in said connector directly controlled over a calling line for connecting either of said sources to said line to selectively signal stations on said line, a cut-off relay in said connector having a winding adapted for inclusion in the signalling circuit and having a locking winding, and circuit arrangements such that both windings of said cut-off relay cooperate when said relay is operated regardless of the source of signalling current used.

5. In a telephone system, a party line, sources of positive and negative signalling current, a connector switch, means for oper-

ating said connector to connect with said line, means in said connector for connecting either of said sources to either side of said line to selectively signal stations on said line, a 5 cut-off relay in said connector having a winding adapted for inclusion in the signalling circuit and having a locking winding, and circuit arrangements such that both windings of said cut-off relay cooperate when said relay 10 is operated regardless of the source of signalling current used.

6. In a party line connector, means for operating the connector in accordance with a digit of a desired telephone number to 15 select a desired line, a ring cut-off relay, a source of positive ringing current, a source of negative ringing current, means operative in accordance with a different digit of the telephone number to select one or the other 20 of the sources of ringing current and connect it to the selected line in series with the ring cut-off relay, and commutating means for maintaining the direction of flow of current through the relay the same regardless 25 of the source used.

7. In a party line connector having a pair of line wipers, means for operating the connector in accordance with a digit of a desired telephone number to select a desired line, a 30 ring cut-off relay, a source of positive ringing current, a source of negative ringing current, means operative in accordance with a different digit of the telephone number to select one or the other of the sources of ringing current and connect it to one or the other 35 of the line wipers in series with the ring cut-off relay, and commutating means for maintaining the direction of flow of current through the relay the same regardless of the 40 source used.

8. In a party line connector, means for operating the connector in accordance with a digit of a desired telephone number to select a desired line, a ring cut-off relay having an 45 operating winding and a holding winding, a source of positive ringing current, a source of negative ringing current, means operative in accordance with a different digit of the telephone number to select one or the other 50 of the sources of ringing current and connect

it to the selected line in series with the operating winding of the ring cut-off relay, and commutating means for maintaining the direction of flow of current through both windings of the cut-off relay the same regardless 55 of the source of ringing current used.

9. An automatic telephone system wherein a connector is operative in accordance with value of certain digits in a party line telephone number to select the line and wherein 60 means is operative in accordance with a different digit of the number to select a source of ringing current to ring the desired station on the line, and wherein a cut-off relay having two windings has one of its windings 65 included in the ringing circuit and is operated over that winding when the called party answers and is locked in its operated position over the second winding, characterized in this, that the ringing current to be selected 70 is either positive or negative current, and commutating means is provided for maintaining the relative direction of the current flow in the two windings the same regardless of the source of ringing current used. 75

10. An automatic telephone system wherein a connector having two line wipers is operative in accordance with the value of certain digits in a party line to select the line and wherein there is means operative in accordance with the value of a different digit in the number to select one of two sources of ringing current and to connect the ringing current source to either of the two wipers 80 and wherein a cut-off relay having two windings has one of its windings included in the ringing circuit to be operated over that winding when the called party answers and is locked in its operated position over the second winding, characterized in this, that the 85 ringing current to be selected is either positive or negative current, and commutating means is provided for maintaining the relative direction of the current flow in the two windings the same regardless of the source 90 of ringing current used. 95

In witness whereof, I hereunto subscribe my name this 8th day of April, A. D., 1926.

CLARENCE E. LOMAX.
